No. 15,093

June 24, 1884

UNITED STATES PATENT OFFICE.

AUGUSTIN LE PRINCE, OF NEW YORK, N. Y.

DESIGN FOR WALL-PAPER.

SPECIFICATION forming part of Design No. 15,093, dated June 24, 1884.

Application filed April 11, 1884. Term of patent 3½ years.

To all whom it may concern:

Be it known that I, AUGUSTIN LE PRINCE, a citizen of the Republic of France, residing in the city of New York, county and State of New York, have invented and produced a new and original Design for Wall or Ceiling Covering, which is especially intended as a dado or frieze.

The drawing represents a front plan view of the design. The motive of this design is suggested by the date-palm. The center part of the design is a representation of branches of the date-palm *a*, bearing clusters of fruit *b* with long ensiform leaves. The direction of the leaves is upward from the base, sweeping backward as they reach the upper portion of the design. Branches in less relief incline in an opposite direction. The foliage overlaps and intermingles in graceful and natural confusion.

20 The groundwork is filled in with line-work drawn horizontally.

The design has an upper border, consisting of a continuous series of horizontal rods, *c*, having a ball, *d*, at their points of junction. 25 These are entwined by two bands of a ribbon form, *e e*. The lower border consists of a series of roundels, *f*, having a rosette center, *g*. These roundels overlap each other, the center

of each one being touched by the outer rim or band of the succeeding one. The overlapping 30 is in the direction of left to right, and the slanting position of the roundels produces a powerful relief on the center.

I claim—

1. The design for a dado or frieze herein shown and described, consisting of the representation of the branches of the date-palm, bearing clusters of fruit with long ensiform leaves extending in various directions through the design and overlapping each other, and a 35 border above and below.

2. The design for a dado or frieze herein shown and described, consisting of the representation of the branches of the date-palm, bearing clusters of fruit with long ensiform 40 leaves extending in various directions through the design and overlapping each other, and a border above the design composed of continuous horizontal rods having balls at their junction, and two ribbons entwining the rod, and a lower border of overlapping roundels having a rosette in their center.

AUGUSTIN LE PRINCE.
